UNITED STATES PATENT OFFICE

ROSCOE C. ZUCKERMAN, OF STOCKTON, CALIFORNIA

SPONGE PAD

Application filed December 15, 1928. Serial No. 326,373.

This invention relates to sponge or absorbent pads for use particularly in washing the outside and adjacent parts of the excretory organs of the human body, my principal object being to provide a pad for the purpose having inherent cleansing and antiseptic qualities, by means of which the parts may be properly washed and sterilized, and which is of a soft and pliable nature so as not to hurt or chafe tender skin; and which is highly absorbent and so constructed that the hand of the user will not be wet or soiled.

A further object of the invention is to provide a pad for the purpose so constructed that when once thoroughly saturated with water and ready for disposal said pad will disintegrate so as not to clog or damage the toilet or other drain pipe down which it may pass.

Also the nature of the pad is such as to permit of a very low cost of manufacture, enabling the same to be marketed at such a price as will put it within the reach of all persons desiring to utilize the same, or so that it may possibly be placed in the toilets of office buildings, clubs and the like for the free use of the tenants or members.

The pads are particularly intended to supplement the use of toilet paper which at best only partly does the work for which it is intended. The use of my improved pad in conjunction with such paper enables those persons so inclined to have clean and immaculate body parts to an extent which under present conditions is impossible to obtain.

These objects I accomplish by means of such structure and relative arrangement of parts as will fully appear by a perusal of the following specification and claims.

In the drawings similar characters of reference indicate corresponding parts in the several views.

Fig. 1 is a fragmentary perspective view of a lavatory showing the installation of my pad dispensing and moistening apparatus in connection with the toilet.

Fig. 2 is a perspective view of one form of the pad.

Fig. 3 is a fragmentary enlarged cross section of the same.

Fig. 4 is a fragmentary cross section of the component parts of the pad shown as partly disassociated from each other.

Fig. 5 is a fragmentary cross section of a modified form of pad.

Fig. 6 is a similar view of still another modified type of pad.

Referring now more particularly at the characters of reference on the drawings, and particularly at present to Figs. 2 to 4 the pad comprises an upper sheet 1 of absorbent fabric, such as cheesecloth, a bottom sheet 2 of oiled or otherwise water proofed paper or equivalent pliable material, and a number of intermediate sheets 3 of absorbent paper punctured roughly as at 4 or so that the paper about the punctures will project outwardly from one face of the sheets. Before the parts are assembled the upper fabric sheet 1 is impregnated with a solution of antiseptic soap indicated at 5. The different sheets of which the pad consists are initially much larger than the individual pad, and after such sheets are assembled in the proper superimposed relation they are cut through simultaneously to the desired size by suitable shearing means, this being done in the presence of steam or other agent if necessary to cause the soap adjacent the edges of the fabric sheet to be temporarily softened to a runny condition. As a result of thus simultaneously cutting the sheets, all of which are of a pliable and porous nature, they are squeezed together around the edges and the fibers at such edges become more or less locked with each other as indicated in Fig. 3, tending to hold them together. In addition to this the semi-dissolved soap from the fabric contacting with all said edges as they are cut binds them firmly together without additional means being necessary.

If desired however any other readily soluble cementing means may be used in place of the soap.

The natural porosity and absorbent nature of the upper and intermediate sheets of the pad enables the same to absorb a considerable quantity of water, while the method of puncturing the intermediate sheets causes them to be held separated somewhat so that the pad

100

is very soft and pliable. When using the pad it is only necessary to apply water to the upper sheet in sufficient quantity to thoroughly dissolve or soften the soap, without going beyond the absorption capacity or saturation point of the pad. The pad may be then applied to the parts to be cleansed. Since the under sheet which is engaged by the hand is of a water proof nature the water will not penetrate through such sheet and the hand will not be wet or soiled. When the pad has served its function it may be thrown into the toilet, when the relatively great quantity of water then present so thoroughly dissolves the remaining soap as to cause the pad to disintegrate and the different sheets to be positively separated from each other. This enables said sheets to be then carried down the drain pipe separately without danger of clogging the pipe.

The pads are particularly intended to be stacked in superimposed relation in a dispensing cabinet 6, with which a small water basin 7 and a water supply faucet 8 are commonly associated. This apparatus is thoroughly described and featured in my co-pending application for patent on the same, Serial No. 326,372, filed Dec. 15, 1928, and is mounted in a lavatory close to the toilet.

The type of pad above described is only one of many forms in which it may be put out.

In Fig. 5 for instance the pad comprises a number of sheets 10 of felted paper bound together as before and of which the upper sheet is saponified, while the lower one is glazed or rendered water proof.

Still another form is illustrated in Fig. 6 in which the pad consists of a number of flat sheets 11 of absorbent material, the upper sheet of which is of a saponified fabric such as cheesecloth, while the other ones are of paper; interposed between the alternate ones of which flat sheets are corrugated sheets 12 of absorbent paper. In the one form the natural thickness and nature of the paper and in the other the corrugating of the alternate sheets, gives the respective pads the necessary thickness, pliability and softness.

While I particularly intend these pads to be used for the above mentioned purpose it will be obvious that they are also very suitable for use in hospitals and in doctors' operating rooms and similar places.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention what

I claim as new and useful and desire to secure by Letters Patent is:

1. A sponge pad comprising a top sheet impregnated with an antiseptic soap, and a pliable water absorbing pad under said sheet.

2. A sponge pad comprising a top sheet impregnated with an antiseptic soap, and a pliable water absorbing pad under said sheet with a water proof sheet under said pad.

3. A sponge pad comprising a top sheet impregnated with an antiseptic soap, a plurality of pliable water absorbing sheets under said top sheet, and means incorporated with said sheets for maintaining them in spaced relation to each other.

4. A sponge pad comprising a top sheet impregnated with an antiseptic soap, and a pliable water absorbing pad under said sheet with means for connecting said sheet and pad together to form a unit only until subjected to a quantity of water in excess of the absorption capacity of the pad.

5. A sponge pad comprising a top sheet impregnated with an antiseptic soap, and a plurality of pliable water absorbing sheets under said top sheet, all said sheets being of a fibrous nature whereby when the sheets are arranged in superimposed order and they are sheared through, the fibers at the sheared edges will tend to interlock with each other to bind the sheets together to form a unitary structure.

6. A sponge pad comprising a top sheet of absorbent material, pliable water-absorbing sheets under the top sheet, all said sheets engaging each other, and a soluble soap with which the top sheet is impregnated and which extends down about the edges of the sheets to bind the same together in pad form.

7. A sponge pad comprising a top sheet of absorbent fabric, a plurality of absorbent paper sheets under the top sheet, a bottom sheet of oiled paper, and a soluble antiseptic soap solution with which the fabric sheet is impregnated.

8. A sponge pad comprising an absorbent pad, one surface of which is treated with a soluble soap, and a flexible waterproof sheet covering the opposite surface.

In testimony whereof I affix my signature.

ROSCOE C. ZUCKERMAN.
